(57) **CLAIM**

The ornamental design for a circle hook, as shown.

DESCRIPTION

FIG. 1 is an isometric front/top view of a circle hook.

FIG. 2 is a side view of the circle hook of FIG. 1.

FIG. 3 is another side view of the circle hook opposite to that shown in FIG. 2.

FIG. 4 is a front view of the circle hook of FIG. 1.

FIG. 5 is a back view of the circle hook of FIG. 1.

FIG. 6 is a top view of the circle hook of FIG. 1; and, FIG. 7 is a bottom view of the circle hook of FIG. 1.

The broken lines and contour shading in the Figures form no part of the claimed design.
